EGG DISPENSING RACK FOR REFRIGERATORS

John Lieber and Roman Lieber, Royal Oak, Mich.

Application January 14, 1953, Serial No. 23,133

Term of patent 14 years

(Cl. D67—3)

To all whom it may concern:

Be it known that we, John Lieber and Roman Lieber, both citizens of the United States, residing at Royal Oak, in the county of Oakland and State of Michigan, have invented a new, original, and ornamental Design for an Egg Dispensing Rack for Refrigerators, of which the following is a specification, reference being made to the accompanying drawing, forming part thereof.

Fig. 1 is a top plan view of the egg dispensing rack for refrigerators, showing our new design;

Fig. 2 is a side elevational view of Fig. 1; and
Fig. 3 is a cross sectional view, taken on line

3—3 of Fig. 2, and showing a portion of the dispensing rack in perspective.

We claim:

The ornamental design for an egg dispensing rack for refrigerators, as shown.
